DESIGN FOR A CAN OPENER

Henning Odencrants, New York, N. Y., assignor
to Zegorav Inc., New York, N. Y., a corporation
of New York

Application July 29, 1947, Serial No. 140,574

Term of patent 14 years

(Cl. D22—2)

To all whom it may concern:

Be it known that I, Henning Odencrants, a citizen of Sweden, residing in the city of New York, county of New York, and State of New York, have invented a new, original, and ornamental Design for a Can Opener, of which the following is a specification, reference being had to the accompanying drawings, forming a part thereof, in which:

Figure 1 is a top plan view of a can opener showing my new design;

Fig. 2 is a side elevational view; and

Fig. 3 is an end view thereof.

The essential features of my design reside in those portions shown in full lines.

I claim:

The ornamental design for a can opener, as shown.

HENNING ODENCRACTS.
